Primary Examiner — Richard Kearney(74) *Attorney, Agent, or Firm* — Justin Lampel(57) **CLAIM**

The ornamental design for an intelligent solar LED lamp, as shown and described.

DESCRIPTION

FIG. 1 is a top plan view of an intelligent solar LED lamp showing my new design;

FIG. 2 is a front elevational view thereof;

FIG. 3 is a left side view thereof;

FIG. 4 is a right side view thereof;

FIG. 5 is a rear elevational view thereof;

FIG. 6 is a bottom plan view thereof; and,

FIG. 7 is a perspective view thereof.

The broken lines illustrating a circular feature on the side surface of the intelligent solar LED lamp, seen in FIG. 4, form no part of the claimed design.
